UNITED STATES PATENT OFFICE.

ALFRED C. EINSTEIN, OF ST. LOUIS, MISSOURI.

FEED MECHANISM FOR ACETYLENE-GAS GENERATORS.

No. 839,565.

Specification of Letters Patent.

Patented Dec. 25, 1906.

Application filed June 27, 1904. Serial No. 214,274.

To all whom it may concern:

Be it known that I, ALFRED C. EINSTEIN, a citizen of the United States, residing in the city of St. Louis and State of Missouri, have 5 invented certain new and useful Improvements in Feed Mechanisms for Acetylene-Gas Generators, of which the following is a full, clear, and exact description, reference being had to the accompanying drawings, 10 forming part of this specification.

My invention relates to mechanism for feeding determined and uniform quantities of calcium carbid in acetylene-gas generators.

15 Figure I is a vertical section taken through parts of an acetylene-gas apparatus with my feed mechanism therein. Fig. II is a horizontal section taken on line II II, Fig. I. Fig. III is a perspective view of the feed- 20 plate. Fig. IV is an elevation showing in detail the escapement mechanism by which the feed-plate is controlled.

25 1 designates a portion of a gasometer-bell of an acetylene-gas apparatus, and 2 is an arm carried by said bell.

30 3 designates a generator-tank, in the upper end of which is a carbid hopper or holder 4. Within said hopper is an inclined chute 5, from which the carbid is discharged at the lower end 6.

35 7 designates an inclined rotatable feed-plate positioned beneath the chute 5 and having its greatest elevation beneath the lower end of said chute, the lower end of the chute being so disposed above the feed-plate that it will discharge carbid thereonto rear- 40 wardly from the highest point of the plate relative to the direction of the plate's rotation. The feed-plate operates through a discharge cut-away portion 4' at the lower end of the hopper 4. Surmounting the feed-plate at its center is a boss 8, and extending from said boss are radial partitions 9, which are preferably of increased height at their 45 inner ends over the height of their outer ends. These partitions subdivide the top surface of the feed-plate into pockets into which carbid falls as it descends from the chute 5. The feed-plate 7 is carried by a rotatable shaft 10, 50 that is journaled in a supporting-frame consisting of bearing members 11 and 12. On the shaft 10 is a bevel-pinion 13, that meshes with a bevel-pinion 14, carried by a horizontal shaft 15, which is journaled in the bearing-yoke 16, secured to the bearing member 12 in the generator-tank 3. The shaft 15 has

fixed to its outer end exterior of the generator-tank an escapement-wheel 17.

18 is an escapement-lever pivoted at 19 to the generator-tank 3. (See Fig. IV.) This 60 lever is provided with pawls 20 and 21, and its outwardly-extending arm is normally yieldingly upheld by a spring 22. The arm of said lever is in a position to be engaged by the arm 2, carried by the gasometer-bell 1, so 65 that when said bell descends upon the occurrence of depletion of gas therein the escapement-lever will be rocked to free the escapement-wheel 17.

In the practical use of my feed mechanism 70 the operation is as follows: Calcium carbid having been introduced into the hopper 4 descends from the chute 5 into the pocket beneath the lower end of said chute until it fills said pocket, and in putting the mechanism in condition for automatic feeding action the feed-plate is rotated sufficiently to cause a series of the pockets to become filled and advanced in the direction indicated by the arrow, Fig. II, toward the discharge cut-away portion 4' of the hopper. Thereafter 80 the carbid is intermittently delivered from the feed-plate, due to the propulsion of the feed-plate by weight action of the carbid lying thereupon in advance of the point of delivery of the carbid, the rotation of the plate being governed by the escapement mechanism when gas becomes depleted in the gasometer-bell to a sufficient degree to occasion 85 descent of the bell until the arm 2, carried 90 thereby, strikes the arm of the escapement-lever 18. When the engagement of these parts occurs, the pawl 20 of the escapement-lever is withdrawn from engagement with a previously-engaged tooth of the escapement-wheel 17, and the pawl 21 is moved to said wheel, at which time the escapement-wheel 95 is freed to permit free rotation of the shafts 15 and 10. The feed-plate is therefore permitted to rotate in a forward direction to a 100 sufficient degree to bring the foremost filled pocket of said plate to the discharge-point of the carbid-hopper, due to the weight-propelling action of the carbid occupying the downwardly-moving portion of the feed-plate. 105

It will be seen that another of the feed-plate pockets will at this time be brought beneath the discharge end of the chute 5 to receive carbid from the chute and be filled ready to advance with the previously-filled 110 pockets. It is also to be noted that after the partially-filled feed-plate has been put in

condition for automatic action by filling the advancing pockets there is constantly a multiplicity of filled pockets in advance of the point of discharge from the chute 5 and only 5 a single filled pocket at the carbide-receiving point, and therefore the weight of carbide in a multiplicity of advancing pockets is an excess of that in a single receiving-pocket, as a consequence of which it is always possible for 10 the carbide upon the advancing portion of the feed-plate to exert, by its greater weight, force for the plate's rotation when the plate-governing mechanism is free.

The partitions 9 serve to subdivide the 15 plate in a manner to provide for accurate discharge of carbide therefrom in determined amounts. Each time that the feed-plate is freed for rotation upon the descent of the gasometer-bell upon the release of the escapement mechanism described sufficient gas again becomes present in the gasometer to 20 elevate its bell. The arm 2 is removed from engagement with the escapement-lever 18, and the spring 22 returns said lever to its normal 25 position, thereby causing the pawl 20 of the lever to again engage the escapement-wheel 17 and hold said wheel from rotation until the bell again descends to renew actuation of the escapement-lever.

30 I claim as my invention—

1. An acetylene-gas generator comprising a carbide-holder having an extension on its lower end, a chute in said holder, and an inclined rotatably-mounted feed member located within the extension of the holder;

40 said extension having a feed-opening therein and the feed-plate having its upper portion located beneath the lower end of said chute and having its lower portion directed toward said feed-opening.

2. An acetylene-gas generator comprising a carbide-holder having an extension on its lower end, a chute in said holder, and an inclined rotatably-mounted feed-plate located 45 within the extension of said holder and divided into compartments; said extension having a feed-opening at its lower end and said feed-plate having its upper portion located directly beneath the lower end of said chute and having its lower portion extending 50 to said feed-opening.

3. An acetylene-gas generator comprising a carbide-holder having an extension on its lower end, a chute in said holder, and an inclined rotatably-mounted feed-plate located 55 within the extension of said holder and having radial partitions dividing the plate into compartments; said extension having a feed-opening at its lower end and said feed-plate having its upper portion located directly beneath the lower end of said chute and having its lower end extending to said feed-opening, 60 whereby the carbide entering at the upper end rotates the feed-plate by gravity and is discharged through the feed-opening at the 65 lower end of the plate.

ALFRED C. EINSTEIN.
